UNITED STATES PATENT OFFICE.

WILLIAM F. KIESEL, JR., OF ALTOONA, PENNSYLVANIA.

STEAM BOILER.

Application filed November 1, 1918. Serial No. 260,670.

To all whom it may concern:

Be it known that I, WILLIAM F. KIESEL, Jr., a citizen of the United States, and residing at Altoona, county of Blair and State of Pennsylvania, have invented certain new and useful Improvements in Steam Boilers, of which the following is a specification.

My invention relates to that class of boilers in which the water space is between an outer shell and an inner shell containing the fire box and the combustion chamber, and my invention consists in means for neutralizing the strains which would otherwise result from longitudinal expansion and contraction of the inner shell and also in limiting by such means the area of communication between the fire box and the combustion chamber, and in the construction of the parts as fully set forth hereinafter, and as illustrated in the accompanying drawing, in which

Fig. 1 is a longitudinal section of part of a locomotive boiler illustrating my improvement;

Fig. 2 is a section on the line 2, 2, Fig. 1; and

Fig. 3 is a perspective view in part section illustrating a particular construction of the distensible connecting member between the two sections of the inner shell of the boiler.

The boiler may be of any usual construction having an internal shell, the longitudinal expansion and contraction of which is desired to be neutralized, and as shown in the drawing is a locomotive boiler having an outer shell A and an inner shell B with the water space between the two, the inner shell containing the fire box *x* and combustion chamber *y*.

The inner shell is in two sections, the front section containing the combustion chamber and the rear section constituting the sides and top of the fire box.

Between the two sections of the inner shell, I interpose a distensible member C which is of plate metal folded so as to produce transversely a hollow U-shaped rib 3 and side flanges 4, 5, which may be riveted to the adjacent ends of the shell section, as shown.

The folded portion or hollow rib 3 is transversely distensible, that is, the sides can separate or be brought together as a result of any contraction or elongation of the shell sections, thereby compensating for these changes and preventing the strains which would otherwise occur.

It is desirable in many instances to contract the passage between the fire chamber and the combustion chamber and in such case the rib 3 is arranged to extend inward. As shown, the lower portion projects inward to a greater extent than the upper, forming in effect a bridge wall.

While the member C may vary in the form, arrangement and proportion of the parts somewhat, I prefer the construction shown in the drawings where the lower portion of the member at the rear extends downward to a point below the level of the grate bars and wholly across the fire box 70 forming the rear face *w* of the latter with side flanges 4, 4 for bolting to the sides of the shell, while the forward portion of the member extends downward to a less extent than the rear portion and is bent forward to form 75 a flange 5 for bolting to the rear end of the shell of the combustion chamber, and the mud ring 6 is bolted between the lower edge of the rear portion of the member C and a flange of the outer shell A of the boiler, as 80 shown.

To facilitate the construction of the member C, I prefer to form it in two sections which are welded together. Thus as shown in Fig. 3, there is an upper section *a* consisting substantially of a metal strip rolled to form the rib 3, and side flanges 8, 8 bent downward at the ends, while the lower section *b* is pressed into shape to form the remaining portion of the rib 3 and side flanges 90 and the fire box back plate *w*. These two sections when brought together and welded along the lines S, S, Fig. 2, constitute a member in one continuous piece. The upper section of the expansion device may therefore be described as a U-shaped expansion element comprising a hollow rib or corrugation extending from end to end of said element and having oppositely projecting lateral flanges. The lower element comprises a 100 vertical front wall *w* having lateral flanges 4 at its vertical ends, a rear wall of less height than the front wall having a flange 5 at its bottom edge and a semicircular wall connecting the tops of said front and rear walls. 105

Although a specific embodiment of the invention has been described in detail it is to be understood that the invention is not thus limited but includes modifications and changes which come within the scope of the 110 appended claims.

Without limiting myself to the construc-

tion and arrangement of parts shown, I claim:

1. An expansion member for connecting the shell sections of a boiler containing the fire box and combustion chamber consisting of two parts welded together, one formed of a strip bent transversely to make a hollow rib and side flanges, and the other bent to form a continuation of said hollow rib and flanges and extending downward and transversely at one side to constitute the front end of the fire box, substantially as set forth.
2. As an article of manufacture, an arch shaped expansion element for the fire-box of a boiler, comprising a vertical front wall having lateral flanges at its vertical ends and a corrugation therein, a rear wall of less height than the front wall having a flange at its bottom edge, and a semicircular wall

connecting the tops of said front and rear walls.

3. In a locomotive boiler having a fire-box and a combustion chamber, an expansion device connecting the inner shells of said fire-box and chamber comprising an upper part and a lower part welded thereto, said upper part consisting of a strip having a hollow rib or corrugation extending from end to end and having oppositely projecting lateral flanges; said lower part comprising an arch shaped element including a vertical front wall having flanges at its vertical ends, a rear wall of less height than the front wall having a flange at its bottom edge, and a curved wall connecting the tops of said front and rear walls.

In testimony whereof I affix my signature.

WILLIAM F. KIESEL, JR.
